(57) **CLAIM**

The ornamental design for a point of sale terminal, as shown.

DESCRIPTION

FIG. 1 is a perspective view of a point of sale terminal showing my new design;

FIG. 2 is a front view of the point of sale terminal of FIG. 1;

FIG. 3 is a back view of the point of sale terminal of FIG. 1;

FIG. 4 is a right side view of the point of sale terminal of FIG. 1;

FIG. 5 is a left side view of the point of sale terminal of FIG. 1; and

FIG. 6 is a top view of the point of sale terminal of FIG. 1; and,

FIG. 7 is a bottom view of the point of sale terminal of FIG. 1.

The broken lines in the drawings are included for illustrative purposes only and form no part of the claimed design.
